UNITED STATES PATENT OFFICE.

CHARLES SCHMIDT, OF CLEVELAND, OHIO, ASSIGNOR TO THE PEERLESS MOTOR CAR COMPANY, OF CLEVELAND, OHIO, A CORPORATION OF WEST VIRGINIA.

LUBRICATING SYSTEM FOR MOTOR-CARS.

No. 885,182.

Specification of Letters Patent.

Patented April 21, 1908.

Application filed December 30, 1907. Serial No. 408,452.

To all whom it may concern:

Be it known that I, CHARLES SCHMIDT, a citizen of the Republic of France, residing at Cleveland, in the county of Cuyahoga and State of Ohio, have invented a certain new and useful Improvement in Lubricating Systems for Motor-Cars, of which the following is a full, clear, and exact description.

The object of the invention is to so improve the lubricating system of a motor car that said car may travel further without the necessity for replenishing the oil, and so that the crank cases may be easily and conveniently supplied with the proper quantity of oil whenever it is necessary to change the oil therein.

The invention consists in the combinations of parts hereinafter described and pointed out definitely in the claims.

20 In the drawing, Figure 1 is a diagrammatic view of the invention,—the engine casing and the crank cases thereof being shown in side elevation, and the other parts in perspective. Fig. 2 is a side elevation partly in section of a mechanical oiler which forms a part of the invention. Fig. 3 is a sectional side elevation of the valve mechanism associated with the oil storage tank; Fig. 4 is a plan view of the valve operating handle and 25 the index associated therewith; and Fig. 5 is a vertical sectional view through one of the valve controlled overflow pipes of the crank cases.

The invention is shown applied to a motor car having a four cylinder motor,—the cylinders being arranged in pairs, and each pair being provided with a crank case, these parts being of familiar construction. The casing A contains cylinders 1 and 2, and is secured over the top of the crank case B. The casing A' contains cylinders 3 and 4 and is secured over the top of the crank case B'. The two crank cases are preferably formed in a single casting, as shown. It will be understood, without illustration that the crank shaft is mounted in bearings in the crank cases.

The mechanical oiler is, generally speaking, of familiar construction; it includes a tank C, which contains the oil pumps, and the operating mechanism therefor. In this tank are four oil forcing pumps D, which respec-

tively force oil into and through several pipes, to wit, pipe F which is branched and which discharges into the two cylinders 1 and 2; 55 pipe F' which is branched and discharges into the two cylinders 3 and 4; pipe F'' which discharges into certain bearings in the crank case B; and the pipe F''' which discharges into certain bearings in the crank case B'. The 60 tank C also contains the main oil pump H whose function is to pump oil from a supply tank into a chamber J, indicated by dotted lines in Fig. 2, in a casing I. This casing is to be secured on one side of the dash board K, while the tank C is secured to the other side thereof.

The tank C contains familiar mechanism for operating the several pump pistons, said mechanism including a shaft M carrying several cams m, which engage with the yokes O attached to the pump pistons. A beveled gear n' is secured to this shaft in mesh with a beveled gear n on a vertical shaft M, which shaft projects through the bottom of the 75 tank and is connected with a flexible shaft n' which receives its power in any suitable manner as from the crank shaft in casing B.

The chamber J discharges oil therein drop by drop through various valve controlled ducts j, said drops falling through glass tubes L into pockets i in the bottom of the casing I. Each of these pockets is connected with the inlet side of one of the pumps D. Heretofore the tank C has contained all of the oil 85 available for use by the mechanical lubricator described. The capacity of this tank has always been limited so as to require filling too frequently to be satisfactory to the car owners. The capacity of this tank has 90 been necessarily limited, by the fact that it is secured to the front side of the dash, where a larger tank cannot be conveniently placed.

Q represents an oil storage tank which may be secured at any convenient and easily accessible point, provided, however, that it must be in a plane above the required level of oil in the crank cases B and B'. A pipe h is connected, at one end, with the inlet side of the main pump H, while its other end extends into tank Q. The outlet side of the main pump H is connected by a suitable pipe or duct h' with the chamber J. This chamber J is provided with an over flow pipe R

which is connected with the tank C; and this tank is provided with an over flow pipe S which discharges into the storage tank Q. There is no inconvenient limit to the possible size of the tank Q. Therefore, when it is once filled, it will hold the oil required for a very long trip without any replenishment.

In the bottom of the tank Q is a valve casing T with which two pipes V and V' are connected,—these pipes discharging respectively into the crank cases B and B'. An ordinary two-way valve W is provided, by means of which oil may be allowed to flow through either of these pipes by gravity into the associated crank case. This valve has a perforated tubular stem w which extends through the top of the tank, and has an operating handle w' on its upper end and an index plate X is secured to the top of the tank beneath this handle.

It is necessary that at certain intervals, the oil in the crank case shall be drawn off and fresh oil supplied. The crank cases are always provided with drainage outlets in their bottoms; and, heretofore, they have had also some sort of capped inlet opening in their tops. At best, these latter openings are inconveniently placed, and the putting of oil into the crank cases through them is always attended by difficulties and inconvenience. With the described construction, however, one has only to turn valve W by means of its handle, and the required oil will flow from the storage tank Q into either crank case. But it is a matter of some importance that neither too much nor too little oil shall be put into each crank case. Glass covered sight openings are sometimes provided to show when the oil is at the proper level. These contrivances for filling crank cases and determining when the proper quantity of oil has been put in, are inconvenient and therefore unsatisfactory. In the construction shown in the drawing each crank case is provided with an over-flow pipe P whose open upper end is at the desired level of oil in the case. In the projecting lower end of each of these overflow pipes is a valve p having an operating handle,—the two operating handles being indicated by p', p'.

The valve W has a second stem w' which extends down through the bottom of the valve casing T. On its lower end is an arm w'. This arm is connected by a rod S with both of the handles p', p'. The latter has preferably a slot p³ in which rod S' lies, and two tapped nuts s, s, are screwed onto the rod on opposite sides of the said handle. These several handles are so arranged on the valves that when valve W is closed both of the valves are closed, but when valve W is turned so as to permit oil to flow into crank case B, the valve p associated with said

crank case will be opened; and when valve W is turned so as to permit oil to flow into crank case B', the valve p associated therewith will be open. Therefore when the oil admitted to either crank case has reached the desired level it will overflow into the associated pipes P, and will drop out of the lower end of said pipe.

Having described my invention, I claim:

1. In a lubricating system for motor cars, the combination with an engine and its crank case, a mechanical oiler which includes a main suction pump and several oil forcing pumps, operating mechanism for said pumps, an oil chamber above said oil forcing pumps, means for delivering regulated quantities of oil from said chamber to the inlet side of said pumps, pipes connecting the outlet side of said pumps with the engine cylinder and bearings in the crank case, an oil storage tank located above the required level of the oil in said crank case, a valve controlled pipe connecting said storage tank with the crank case, a pipe connecting said storage tank with the inlet side of the main pump, a duct connecting the outlet side of said pump with said oil chamber, and means for conducting the overflow from said chamber back into said storage tank.

2. In a lubricating system for motor cars, the combination of the engines and crank cases, a tank containing a main pump and several oil forcing pumps and operating mechanism therefor, an oil chamber located above said tank, means for delivering regulated quantities of oil from said chamber to the inlet side of said oil forcing pumps, pipes connecting the outlet sides of said oil forcing pumps with the engine cylinders and with bearings in the crank cases, an over flow pipe leading from said chamber to said tank, an oil storage tank located in a plane above the required level of oil in said crank cases, two pipes connecting said storage tank with the two crank cases, a two-way valve for controlling the flow of oil through said pipes, a pipe connecting said storage tank with the inlet side of the main pump, a duct connecting the outlet side of said pump with said oil chamber, and an over flow pipe connecting the oil tank first mentioned with the oil storage tank.

3. In an automobile, the combination of an oil storage tank, a crank case, a pipe connecting the tank and crank case, a valve controlling the flow of oil from the tank into said pipe, an overflow pipe for said crank case, a valve for said pipe, and connections between said valves to compel them to operate in unison, substantially as specified.

4. In an automobile, the combination of an oil storage tank, two crank cases, a valve casing connected with said tank, two pipes

connecting said tank with the two crank cases, a valve controlling the flow of oil into said pipes, an overflow pipe in each crank case, a valve in each overflow pipe, and mechanism connecting the tank valve with both of the other valves, substantially as specified.

In testimony whereof, I hereunto affix my signature in the presence of two witnesses:

CHARLES SCHMIDT.
